(57) **CLAIM**

The ornamental design for a paw print jewelry bail, as shown and described.

DESCRIPTION

FIG. 1 is a perspective view of a paw print jewelry bail, showing our new design.

FIG. 2 is a front elevational view;

FIG. 3 is a side elevational view;

FIG. 4 is a rear elevational view; and,

FIG. 5 is a top plan view.

All portions shown in broken lines form no part of the claimed design.
